UNITED STATES PATENT OFFICE.

ANDERS NICOLAY ANDERSEN, OF HOUGHSUND, EKER, AND CHRISTIAN VIG, OF SKOTFOS, NORWAY.

MACHINE FOR LONGITUDINAL GRINDING OF WOOD LOGS.

1,263,357.

Specification of Letters Patent. Patented Apr. 23, 1918.

Application filed July 14, 1916. Serial No. 109,350.

To all whom it may concern:

Be it known that we, ANDERS NICOLAY ANDERSEN, a subject of the King of Norway, residing at Houghsund, Eker, and 5 CHRISTIAN VIG, a subject of the King of Norway, residing at Skotfos, Norway, have invented certain new and useful Improvements in Machines for Longitudinal Grinding of Wood Logs; and we do hereby de- 10clare the following to be a full, clear, and exact description of the invention, such as will enable others skilled in the art to which it appertains to make and use the same, reference being had to the accompanying 15 drawings, and to letters or figures of reference marked thereon, which form a part of this specification.

The present invention relates to grinding machines for longitudinal grinding of wood logs and the object of the invention is to provide a machine of this type in which the circular periphery of the rotating grind- 20stone will cut the fibers of the wood sub- jected to its grinding action in the same di- 25rection.

The advantage of longitudinal grinding in the same direction as the wood fibers consists therein that the fibers obtained are longer and finer than the fibers obtained in 30 the ordinary transverse grinding processes. This is due to the fact, that in transverse processes the unevennesses in the grinding surface will break up and cut the fibers so that the same are not extracted in their 35 whole length.

Longitudinal grinding is mostly per- formed on the flat side of a grind stone. It is however clear that when grinding on the flat side of the rotating stone the active 40 parts of the grind stone will not all move in the same direction as the fibers, as the fibers lie in a straight line, while the several parts of the grind stone move in arcs. The ideal effect cannot be obtained in this man- 45ner.

On the other hand when grinding longitudinally on the cylindrical surface on the grindstone, if the wood were first to touch the grinding surface with any point be- 50tween its ends, it will be seen that the part of the wood behind this point would be ground against the fibers, whereby the fibers

will be broken so that the desired effect is not obtained. Therefore, in order to obtain the best grinding action, the wood must first 55 touch the grinding surface with its rear- most end, that is, the position of the wood with regard to the grinding surface must be such that the fibers in the rearmost end of the wood form tangents to the grinding 60 surface.

In order to obtain this effect in grinding machines of the ordinary kind in which the grinding pockets are placed radially with regard to the grindstone, the front surface 65 of the pressing pistons according to the present invention is arranged at a certain angle to the axis of the grinding pocket in such a manner, that, when pushed to its innermost position, the front surface of the 70 grinding piston will touch the grindstone with its rearmost part taken in the direction of the movement of the grinding surface.

This object is attained by arranging 75 the pressing pistons in the radial pockets of the grinding machine at such an angle to the axis of the grinding pocket that the rearmost fibers of the wood logs as seen in the direction of movement of the grinding surface are approximately parallel to the 80 same.

On the drawing the invention is illus- trated by means of a diagrammatical sketch.

A indicates the wood logs.

B is the pressing piston, D is the pocket 85 and C is the grindstone.

As it will be noted the pressing piston B is arranged at an angle to the walls of the pressing pocket D, and as the wood logs A are parallel to the pressing piston they will 90 also lie at an angle to the walls and to the axis of the pocket. This angle is so chosen, that the fibers at the rearmost part E of the logs subjected to the grinding action are sub- 95 stantially parallel to the grinding surface or so that the log at this point is at least not ground against its fibers.

The invention may easily be applied on old grinding machines of the usual type by changing the pistons of the same.

Although the invention is here shown as applied on a grinding machine in which the wood is ground on the circumference of the grindstone, it will however be understood

that it may also be adapted on machines where the wood is ground on the flat sides of the grind stone.

Claim:

- 5 In a machine for longitudinally grinding wood logs, the combination with a cylindrical rotatable grind stone, of a stationary pocket for the logs to be ground having its longitudinal axis in a radius of said stone and its sides parallel to said axis, and a 10 radially movable pressure piston in the pocket having its forward end arranged obliquely to said axis and converging toward

the grinding surface in the direction of movement of the latter, whereby the rear-most part of the log is first moved into contact with said surface. 15

In testimony that we claim the foregoing as our invention, we have signed our names in presence of two subscribing witnesses. 20
